Des. 180,619
Patented July 9, 1957

180,619

DISPENSING MACHINE FOR BALL GUM AND THE LIKE

Harold T. Probasco, Los Angeles, Calif., assignor to Oak Manufacturing Co., Inc., Culver City, Calif., a corporation of California

Application September 28, 1956, Serial No. 43,128

Term of patent 14 years

(Cl. D52—3)

Fig. 1.

Fig. 2.

Fig. 3.

Fig. 4.

Fig. 1 is a front elevational view of a dispensing maine for ball gum and the like, showing my new design;
Fig. 2 is a side elevational view;

Fig. 3 is a top plan views; and

Fig. 4 is a rear elevational view thereof on a reduced scale.

I claim:

The ornamental design for a dispensing machine for ball gum and the like, as shown.
